UNITED STATES PATENT OFFICE.

CHARLES T. BLOOMER, OF NEWARK, NEW YORK.

PAPER BOX.

1,115,163.

Specification of Letters Patent.

Patented Oct. 27, 1914.

Application filed April 24, 1914. Serial No. 834,171.

To all whom it may concern:

Be it known that I, CHARLES T. BLOOMER, a citizen of the United States, residing at Newark, in the county of Wayne and State 5 of New York, have invented a new and useful Paper Box, of which the following is a specification.

The present invention appertains to paper boxes or receptacles, and aims to provide a 10 novel and improved means for holding closed, the cover or top of the box or container.

The present invention contemplates the provision of simple and inexpensive means 15 whereby the free portion of a swinging cover or lid of a paper box or receptacle, may be fastened in place, when the cover or lid is closed, and whereby the cover will be held in closed position in a thoroughly efficient and practical, but simple manner.

It is also the object of the present invention, to provide a fastening means of the nature indicated, which will not only be simple, but which will not appreciably encumber the box or container, when the cover is fastened in closed condition, whereby, the box when closed, will present a neat appearance, and whereby it is necessary to mutilate the box, to release the cover, when once 25 closed and fastened, in order that when the box has been filled and closed, the same may not be opened by malicious or unauthorized persons, without the box being so mutilated, as to enable the tampering with the box or 30 its contents to be detected by the purchaser or recipient.

As a more specific object, the present invention has in view, the provision of a metallic tongue or fastener arranged to swing 40 through the cover and into the box, for fastening the cover in closed condition, in connection with means for closing that portion of the cover through which the tongue is bendable, in order that the cover opening, 45 will not present an objectionable appearance, and in order that the tongue or fastener cannot be readily released without mutilating the box or its cover.

With the foregoing and other objects in 50 view which will appear as the description proceeds, the invention resides in the combination and arrangement of parts and in the details of construction hereinafter described and claimed, it being understood 55 that changes in the precise embodiment of

the invention herein disclosed, can be made within the scope of what is claimed, without departing from the spirit of the invention.

The invention has been illustrated in its 60 preferred embodiment in the accompanying drawings, wherein:—

Figure 1 is a perspective view of a paper receptacle or container, in the form of an egg box, and incorporating the present improvements, the cover being shown in opened position. Fig. 2 is a perspective view of the box or receptacle with the cover closed, and illustrating the tongue or fastener being bent to lock or fasten the cover in closed 70 condition. Fig. 3 is a cross section of the receptacle or box, along the central portion thereof. Fig. 4 is a sectional view taken on the line 4—4 of Fig. 3. Fig. 5 is a fragmental detail illustrating a modification. 75

In the drawings, the numeral 1 designates a paper receptacle or container, which may be of any suitable character, and which is illustrated in the form of a rectangular egg box, preferably of foldable or collapsible 80 formation. The back wall of the box or receptacle 1 is provided with a swinging cover or top 2, which is provided at its free portion with a tuck flap 3 insertible into the box or receptacle against the inner face of 85 the front wall of the box, when the cover 2 is closed.

The egg box 1 has disposed therein a cellular rack or filler 4 constituting longitudinal and lateral partitions, as usual, providing the cells or pockets for receiving the eggs or other commodities. 90

The fastening means includes a metallic tongue or fastener 5, which is preferably, although not necessarily, secured to the 95 inner face of the front wall of the box by clenching prongs 6 from the tongue 5 through the front wall of the box. The upper or free end portion of the tongue 5 up-stands from the upper edge of the front wall 100 of the box above the cover line or plane, the tuck flap 3 of the cover 2 being insertible in rear of the tongue 5 when the cover is closed, so as to assume a position between the filler or rack 4 and the front wall of the box and 105 tongue 5. The tongue 5 is preferably disposed midway between the ends of the box, although not necessarily so.

The cover 2 of the box is provided with tongue-receiving means, and to this end, the 110

cover is provided with an H-shaped slit or cut 7 midway between its ends and adjacent the tuck flap 3 and the front wall of the box. The longitudinal portions of the slit 7 are preferably parallel with the fold line of the flap 3, one longitudinal portion preferably lying in the fold line of the said flap. The slit 7 provides opposed flexible tabs 8, which project toward each other adjacent the flap 3, and which when they are bent out of the plane of the cover 2, provide an opening in the cover 2 adjacent the flap 3 for the reception or passage of the free portion of the tongue 5.

15 As a means for limiting the downward movement of the tabs 8, when the cover 2 is closed, and for assisting in causing the tabs 8 to assume their normal closed positions, the outermost longitudinal partitions 20 9 of the filler or rack 4, and the central or median lateral or cross partition 10 are provided with complementing cut-away portions or notches 11 and 11^a at the upper and lower edges. The cut-away portions or 25 notches 11 and 11^a are modifications, either form being employed, as desired, it being noted that one set of the coöperating cut-away portions or notches 11 or 11^a will always be disposed adjacent the tongue or 30 fastener 5 notwithstanding the fact that the filler or rack might be inserted with either side up, or in reversed longitudinal positions. However, when the rack or filler 4 is disposed within the box 1, only one set of 35 cut-away portions or notches 11 are operative or employed, it being desirable, however, to provide the several sets of notches 11 or 11^a in order to eliminate the accurate placing of the rack or filler within the box.

40 In use, after the box has been filled, and when it is desired to close the same, the cover 2 is folded over the mouth of the box, and the flap 3 is tucked between the front wall of the box and the rack or filler 4, the flap 45 3 passing in back of the tongue 5, in order that the upper or free end of the tongue will project above the cover when it is closed. It is then an easy matter to lock or fasten the free portion of the cover 2 in place, by applying the finger to the outer side of the free portion of the tongue 5 and bending the free portion of the tongue over the upper or basal edge of the flap 3 and thence downwardly against and between the tabs 8, as 50 seen in Fig. 2. When the tongue 5 is bent downwardly within the opening formed by the slit 7 and tabs 8, the tabs 8 will yield or flex downwardly to permit of the passage of the free portion of the tongue 5 beyond the tabs and against the inner face of the flap 3, as 55 seen in Fig. 3, to hold the flap 3 in place, and to thereby hold the cover 2 in closed position. When the free portion of the tongue 5 has been bent or clamped 60 against the inner face of the flap 3, and

when the finger has been withdrawn, the tabs 8 which possess more or less resilience, will tend to assume their normal closed positions, this being facilitated by the fact that when the tabs 8 are swung downwardly, they will contact with the cut-away portions 11 of the adjacent partition 9, which will not only limit the downward movement of the tabs 8, but which will assist in returning the tabs 8 to normal or initial position. The cut-away portions 11 are preferably such, that when the tabs 8 are depressed, the portions of the partition 9 adjacent the tongue, adjacent the cut-away portions or notches 11, will yield slightly to enable the tabs 8 to be depressed sufficiently for the passage of the free portion of the tongue 5, whereby when the tongue has been properly bent, as seen in Fig. 3, and the finger withdrawn, the tabs 8 will be thrown back to restore them to their closed positions.

Although the two tabs 8 are intended to bend simultaneously for the passage of the tongue therebetween, it will be apparent that either of the tabs may bend by itself to this end.

It is to be observed that the tabs 8 are opened by the same pressure of the finger that is employed for bending the tongue 5 into engagement with the cover, the operation being a simple and expeditious one. When the tongue 5 has been bent properly, to hold the cover closed, and when the tabs 8 resume their normal closed position, the free portion of the tongue 5 will be protected by the tabs 8, to prevent or impede the prying up or unbending of the tongue, without mutilating the tabs 8 or the adjacent portions of the cover or front wall of the box. Should a maliciously inclined person attempt to release the tongue 5, after the same has been bent to lock the cover, it would be necessary to depress the tabs 8 excessively, to get at the free end of the tongue, which in the first place, is more or less difficult, and furthermore, due to the fact that the downward movement of the tabs 8 is limited, ready access to the free end of the tongue cannot be had without mutilating the tabs 8 or other parts of the box.

It will of course be understood that the fastening means may be utilized for holding the cover 2 closed, without the assistance of the filler or rack 4, the tabs 8 tending to return to their original position, due to their flexibility or inherent tendency to maintain their normal condition, unless bent beyond a certain degree. The employment of the fastening means in connection with an egg box is particularly advantageous, inasmuch as the filler or rack is employed in a unique manner in connection with the fastening means, for limiting the movement of the tabs 8 and for assisting in returning the tabs to normal condition, as well as preventing the

prying up or unbending of the tongue, as will be obvious from the foregoing explanation.

After the box has once been closed and the cover fastened, it is a difficult, if not impossible matter for an unauthorized or malicious person to open the cover, to tamper with or to substitute the contents of the box, without so mutilating the tabs 8, or other parts, as to cause the tampering to be detected by the purchaser or recipient of the box of eggs or the like. The advantages of this feature are obvious, it being noted that with the box as illustrated, fresh eggs may be boxed with the assurance that the eggs cannot be replaced by storage eggs, without the substitution being detected due to the mutilation of the box.

To open the box or package readily, it is preferable to slip one finger along the inside of the box between the front wall of the box and the cover flap near one end of the box, and then moving the finger toward the center of the box, so as to tear the front wall of the box loose from the tongue 5, which will allow the cover to be readily opened, carrying with it, the tongue 5. This also assures the destruction of the box for further use, as far as the fastening means is concerned.

The numerous advantages and capabilities of the present invention will be obvious to those versed in the art, without further or extensive comment being necessary, it being noted that the objects aimed at have been carried out satisfactorily by the provision of the peculiar structure herein disclosed.

In the variation illustrated in Fig. 5, the cover 2 is provided adjacent the flap 3 with an arcuate slot 7' forming a semi-circular tab 8' adapted to be bent inwardly with the tongue 5. This form is of advantage in a number of respects, as will be obvious from the foregoing.

Having thus described the invention, what is claimed as new is:—

1. A box having a cover, a bendable tongue carried by one wall of the box, the cover having a tab adjacent the said wall forming an opening through which the tongue is adapted to be bent to hold the cover closed, the tab being flexible to permit of the passage of the tongue through the said opening and to

then close the said opening to impede the unbending of the tongue.

2. A box having a cover, a bendable tongue carried by one wall of the box, the cover having a pair of opposed tabs adjacent the said wall forming an opening through which the tongue is adapted to be bent between the tabs to hold the cover closed, the tabs being flexible to permit of the passage of the tongue therebetween and to then close the said opening to impede the unbending of the tongue.

3. A box having a cover, a bendable tongue secured to one wall of the box, the cover having an opening adjacent the said wall through which the tongue is adapted to be bent to hold the cover closed, and means for closing the said opening after the tongue is passed therethrough to impede the unbending of the tongue.

4. A box having a cover, a bendable tongue carried by one wall of the box, the cover having a tab adjacent the said wall forming an opening through which the tongue is adapted to be bent to hold the cover closed, the tab being flexible to permit of the passage of the tongue through the said opening and to close the said opening to impede the unbending of the tongue, and means within the box for limiting the movement of the said tab and for assisting in returning the same to normal position for closing the said opening.

5. A box having a cover, a bendable tongue carried by one wall of the box, the cover having a tab adjacent the said wall forming an opening through which the tongue is adapted to be bent to hold the cover closed, the tab being flexible to permit of the passage of the tongue through the said opening and to close the said opening to impede the unbending of the tongue, and a filler within the box having a cut away portion for receiving the said tab to limit the movement of the said tab and to assist in returning the tab to normal position for closing the said opening.

In testimony that I claim the foregoing as my own, I have hereto affixed my signature in the presence of two witnesses.

CHARLES T. BLOOMER.
